HIGH DENSITY BEAM TUBE

Karl Spangenberg, Lester M. Field, and Robert Helm, Palo Alto, Calif., assignors to International Standard Electric Corporation, New York, N. Y., a corporation of Delaware

Application June 15, 1942, Serial No. 447,194

14 Claims. (Cl. 315—16)

1

This invention relates to electron beam tubes, more particularly to tubes such as the velocity modulation type wherein the electron beam traverses a field-free space for a comparatively great distance.

In tubes of these types it is desirable to produce an electron beam of high density, that is a beam having as little spread as possible, somewhat analogously to the production of a high concentrated beam of light for projection over a distance. Such tubes are of great use in the electronic art, examples being velocity modulation tube beam-power transmitting and receiving tubes, television projecting tubes, high-intensity X-ray tubes, and other similar devices.

In tubes of the types just mentioned, maximum efficiency and control depend, *inter alia*, upon the production of an electron beam of relatively small cross section, carrying as high a current as possible at as low a potential as possible, *i. e.* a relatively low impedance electron beam. In such tubes the production of a beam of this type is beset with several difficulties, one greatly detrimental factor being the tendency of the beam, once produced, to spread out as it progresses along the length of the tube, due to the mutually repellent action caused by the space charge effect of the electrons in the beam.

As one means of preventing this spreading out of the electron beam, the art has depended to a large extent upon the ionization of molecules of residual gas within the tube, the positive ions formed by the impact of electrons from the beam upon such gas molecules tending to neutralize the negative charges of the beam electrons and thus tending to prevent the mutual repulsion of the latter. The problem has been complicated by the question of the degree of vacuum existing within the tube, the number of positive ions produced being dependent upon the number of residual gas molecules present. Several factors have contributed to the production of tubes with increasingly high vacua and at these higher vacua fewer positive ions are produced, so that this remedy for beam-spread has become decreasingly potent in its effect.

With the advent of tubes embodying a field-free region, such as the drift tube of a velocity modulation tube it had been assumed that the generally practiced enclosure of such field-free space by a conductive tube would allow the positive ions produced from residual gas to collect within such tube and therefore would cause them to exert a greater and more continued restraining action upon the undesirable spread of the elec-

2

tron beam. Experience with cathode ray tubes incorporating drift tubes of substantial length, has shown, however, that the beam spread continues to take place to an undesirable degree and that the positive ions fail to exert upon the electron stream the restraining action to the extent which they should do, according to the theory above outlined.

The existence of undesirable beam spread in tubes of this type has become a detrimental factor whose importance has increased with the use of higher vacua and increasing currents. More specifically, well known formulae for the degree of ionization taking place under conditions existing in a moderately high powered velocity modulation tube, show that there should be produced sufficient positive ions to neutralize the charges within the electron beam, provided that the gas pressure be not reduced much below 10^{-7} mm./Hg, a degree of vacuum near which commercial tubes are expected to operate.

The discrepancy between the remedial effect of gas ionization postulated by theory and the actual insufficient effect produced in practice has hitherto remained unsatisfactorily explained, although several reasons for its occurrence have been suggested. Lacking any satisfactory explanation for this undesirable phenomenon, no way has been found in the prior art of overcoming the same by purely electro-static means and recourse to electromagnetic concentrating devices has been found necessary.

Our invention is designed to overcome, solely by electrostatic means, the beam-spread difficulty above described and the modus operandi thereof is hereinafter set forth.

Our invention has for one object the production of an electron beam of low impedance and the propagation of such beam over a relatively great distance through a field-free space enclosed by a conducting shield.

Another object of our invention is the provision of an electrical circuit and determination of the constants thereof, which may be applied to an electron beam tube in order substantially to reduce or practically wholly to prevent undesired electron beam spread within such tube.

Yet another object of this invention is to provide a method and means for trapping and confining within a predetermined region positive gas ions produced in an electron beam tube.

Yet another purpose of our invention is to provide quantitative data from which the design, construction and operating constants of an electron beam tube may be predicated in such fashion

as to limit the beam-spread therein to any desired or predetermined degree.

Another purpose of our invention is to increase the efficiency of electron beam tubes and to reduce the impedance of the electron beam therein, by keeping the beam highly concentrated and therefore of low impedance.

A still further object is to produce upon the target or screen of a cathode ray tube, an illuminated spot reduced in size to substantially that of the cross-section of the beam as initially generated, without the necessity of employing electromagnetic beam concentrating means to secure this result.

Another object is to provide means and a method for limiting the cross section of an electron beam to any desired degree commensurate with the current carried thereby, by the employment of purely electrostatic means.

Still another object is to provide means for maintaining a dense electron beam in extremely good vacua, such as 10^{-9} mm./Hg.

Fig. 1 is a diagrammatic representation showing one form of cathode ray tube, embodying our invention and also showing the axial potential distribution thereof when connected according to our invention.

Fig. 2 shows a family of curves illustrating the beam-spread effects observed with a tube constructed and operated according to the prior art.

Fig. 3 shows the beam-spread effect due to mutual electron repulsion, in the absence of positive ion effect, of an initially parallel electron beam.

Fig. 4 is a nomograph showing the beam-spread effect corresponding to a given potential, total current and beam length in the absence of positive ion effect, of an initially parallel electron beam.

Fig. 5 shows graphically beam-spread effects as observed and as calculated according to the theory of operation of our invention.

In deriving the data upon which our conclusions as to the cause of the difficulties encountered in the prior art with electron beam-spread were based and in deriving formulae useful for the design of electron tubes for overcoming these difficulties according to our invention, the following conclusions were first reached from theoretical considerations and were then tested experimentally as to the correctness thereof.

For a typical electron beam, one having the following characteristics was chosen as an example:

Area—1 cm. ²	Produced in a gas pressure of 10^{-6} mm./Hg
Current—0.05 ampere	
Potential—6000 volts	

The first point to be considered is at what pressure enough gas molecules will be found present so as to furnish a sufficient quantity of positive ions completely to neutralize the electron charges of such beam. Formulae well known in the electronic art give the number of electrons existing at a given instant in one cm. of such beam as 6.82×10^{-7} . Likewise a well known formula of physics gives the number of gas molecules per cm.³ at 10^{-6} mm./Hg as 3.55×10^{10} . From a consideration of these two values it is seen that the tube in which the above described beam is to be produced would have to be pumped to a vacuum between 10^{-8} and 10^{-9} mm./Hg before there would be present an insufficient quantity of gas molecules to supply a quantity of positive ions

great enough to neutralize all the electron charges present in the beam.

The next question arising is concerning the actual number of ions which will be formed under the above stated conditions. This value may be found by the formula set forth by S. H. Bennett in an article entitled "Magnetically self focusing streams" and published in Phys. Rev., vol. 45, No. 12, June 15, 1934, pp. 890-897.

According to this formula the number of ions formed per cm. length of beam per second is equal to

$$\frac{200 \pi i}{Ve}$$

in which p is the pressure expressed in mm./Hg; i is the current expressed in E. S. U.; V is the potential expressed in E. S. U.; and e is the electronic charge, also expressed in E. S. U.

Applying this formula to the instant assumed case, it is found that 3.14×10^{12} ions are formed per cm. length per second. Although the life period of ions under such conditions and with an allowance for any possible existence of recombination, is of the order of one second, the foregoing values derived from the electron count and the speed of production of ions, show that each ion need live only

$$\frac{6.82 \times 10^{-7}}{3.14 \times 10^{12}} = 2.17 \times 10^{-15} \text{ seconds}$$

in order to maintain complete neutralization of the beam.

The foregoing mathematical investigations of this particular point prove that sufficient ionization should take place to prevent beam-spread, until the gas pressure is reduced to at least 10^{-8} mm./Hg, which degree of vacuum would result in there being present too few molecules to provide the necessary ions for complete electron neutralization. Now commercial tubes of the electron beam types usually operate at pressures of about 10^{-7} mm./Hg and yet it is well known that some tubes actually do display detrimental beam-spread effects as soon as the pressure is reduced below 10^{-5} mm./Hg. We have made careful experimental determination upon such tubes provided with a field-free space or drift tube especially well shielded and yet the beam-spread effect reached noticeable proportions as soon as the gas pressure was reduced to a point lying between 10^{-6} and 10^{-7} mm./Hg.

In Fig. 1 there is shown as one example of our invention an electron tube having a cathode structure 10, a first accelerating electrode 11, held at 1000 volts positive potential relative to the cathode, a second accelerating electrode 12, held at 5000 volts additional positive potential and provided with an apertured end structure 13, a drift tube 14 held at about 15 volts negative relative to the electrode 12, and a target or collecting electrode 15, held at the same potential as electrode 12.

The axial potential distribution, as shown by the graph, starts at point 16 at zero potential, rises as shown at 17 when electrode 11 is reached, rises again sharply as shown at 18, until at structure 13 the maximum potential is reached, shown by peak 19. There is then a reversal of potential gradient to the level 20, existing throughout the drift tube 14, and again a rise of gradient to point 21, corresponding to the potential of target 15 and equal to that applied to electrode 12.

For a better understanding of the operation of the device of Fig. 1, reference is made to Fig.

2, where are plotted the experimentally determined beam-spread effects found in an electron tube similar to that of Fig. 1, but having the drift tube maintained at the same potential as the electrodes situated adjacent to each end thereof, respectively, this mode of connection being that commonly used in the prior art.

From the graphs shown in Fig. 2 it will be noted as the gas pressure is decreased while the potential is held constant, the beam-spread effect increases at a rate which varies according to the particular potential employed. The drift tube potential shown in Fig. 1 was varied in the derivation of these graphs. At lower potentials the beam-spread effect is barely noticeable until the pressure is reduced to about 10^{-6} mm./Hg and increases comparatively slowly as the pressure is further reduced. At higher potentials the beam-spread effect starts at about the same degree of vacuum, but rises comparatively rapidly to a greater value, reaching its limiting value of approximately $R/R_0 = 3$ for a 6100 volt, 100 milliamperes beam before the pressure has been reduced by the factor of 10. These effects of beam-spread are partially explicable from the fact that over this range of voltages the probability of ionization varies inversely as the voltage and undoubtedly a still higher maximum beam-spread would be reached if the vacuum were pushed further. When the voltage is increased above 6100 volts the beam tends to reach its limiting spread quite rapidly and this limiting spread is considerably smaller than that reached around 6100 volts, this latter effect being that which would be expected from ordinary space-charge beam-spread considerations, independently of any positive ion phenomena.

As previously stated, mathematical analysis shows that there should be substantially zero beam-spread at pressures below 10^{-8} mm./Hg, due to the positive ions formed. Yet the results plotted in Fig. 2 clearly indicate that for some reason the positive ions fail to operate in the manner assumed by the considerations upon which the prior art has been based.

In Fig. 3 in which Z is the axial length of the beam there is shown a graph illustrating the theoretical beam-spread effect in the absence of positive ionization. Theory shows that spreading beams are reducible to the shape illustrated by the graph by a suitable change of vertical and horizontal scale factors. Further in any given structure if the potential be changed by a given factor the current, if from a space charge limited source will in turn change in such a way that the shape of the beam is not in any way altered. We have experimentally verified this rather astonishing conclusion. The graph of Fig. 3 can likewise be used for initially convergent beams, provided that the beam electrons are initially so directed that in the absence of electrostatic repulsion they would converge to a point, since such beams become parallel at some point and thereafter diverge.

In Fig. 4 there is shown a diagram which allows the beam-spread effect to be computed for a given potential, total current and beam length. The laws illustrated in Figs. 3 and 4 serve to explain some of the beam-spread effects shown by the graph of Fig. 2, but still leave unexplained the occurrence of very appreciable beam-spread at pressures lying between 10^{-6} mm./Hg and 10^{-7} mm./Hg, since considerations previously discussed indicate that over this range of pressures there exists a sufficient quantity of positive ions

confined within the drift tube, to neutralize completely the negative charges of the electrons in the beam. These considerations, then, which have been assumed to be correct by the prior art, show that comparatively complete neutralization of the space-charge effect in the electron beam should obviate the occurrence of appreciable beam-spread at pressures in the neighborhood of 10^{-7} mm./Hg.

- 5 10 We are thus confronted with serious discrepancies between the assumptions upon which the prior art structures were designed and connected for operation, and the actual results obtained in practice, such results including the extremely 15 detrimental and undesirable spreading of the electron beam to a very great degree, with consequent failure to maintain the desired high density and low impedance of the electron beam.
- 20 After the consideration of several possible tentative explanations for this discrepancy, all yielding negative results, we arrived at the conclusion that the positive ions were removed axially from the portions of the electron beam adjacent to the entrance end of the drift tube, and that 25 as the positive ions were so removed, other ions from the more central portion of the beam were fed axially along the beam so as to reach the portions thereof near the ends of the drift tube, where these ions in turn were swept out and removed. This process just described amounts 30 then to a continual leakage of positive ions along the electron beam in an axial direction until such ions reached points lying without the drift tube. This means that complete neutralization 35 of the space-charge effects tending to produce divergence of a portion of the electron beam lying within the drift tube, will not take place according to the conclusions above reached mathematically, since the quantity of ions available at pressures below 10^{-6} mm./Hg will be insufficient to take care of this continual axial leakage or loss of ions from the interior of the drift tube.

40 Referring again to Fig. 1, it will be seen that we have established at the respective ends of the drift tube, a reverse potential gradient. We have found that this comparatively low reverse potential gradient serves to trap the positive ions within the drift tube and thus substantially to prevent the removal of positive ions from the interior of the drift tube by leakage of ions in an axial direction along the electron beam and thus substantially to prevent beam-spread at the degree of vacua employed in ordinary practice, for 45 example 10^{-7} mm./Hg.

50 While we believe this theoretical explanation just given of the trapping action of our reverse potential gradients to be a substantially correct one, yet we do not confine ourselves to such theory, but we have found by actual successful experimentation, that a cathode ray tube arranged and connected in accordance with the principles illustrated in Fig. 1, actually does virtually completely prevent the undesirable beam-spread effect encountered in the prior art. By 55 the employment of our invention, it is unnecessary to employ the magnetic fields found necessary by the prior art in order to maintain a high density beam having low impedance.

60 According to another viewpoint, an explanation of the removal of positive ions from the interior of the field-free space constituted by the drift tube may be found by considering that there exists adjacent the beam opening at one end of the drift tube an external field which extends

over a small distance into the field-free space and which field tends continuously to remove ions from the portion of the beam adjacent this point. The existence of such a field at the aperture at which the electron beam first enters the drift tube may readily be predicated from the electron accelerating field existing in the near vicinity of this point. When such field removes the ions from the center of the beam, the center of the beam will become more negative in potential, thereby causing a flow to the center of the beam of ions from other sections of the beam. In other words, the mechanism of ion removal may be considered in the guise of an ion sink toward which ions from all points in the electron beam will start flowing. From these considerations it will be apparent that ion removal from the electron beam may take place over distances far greater than the distance to which the actual external field penetrates within the drift tube.

We have determined mathematically, following the data to be derived from the above theory, what would be the approximate beam-spread action of such mechanism upon an electron beam having given constants. In Fig. 5 are shown graphs illustrating the beam-spread action measured in some cases and calculated according to the mathematical method above referred to, in other cases. It will be observed that the measured and calculated values are in close accordance with one another, thus tending to substantiate the correctness of our theory of an ion sink above stated.

Our mathematically derived conclusions allow us to predict the general shape and approximate values of the curves of Fig. 2. As the voltage is lowered, not only is the effect much the same as an increase of pressure would have had in reducing beam-spread, but also the potential gradient at the drift tube aperture is lowered in direct proportion to the voltage decrease, thus still further accentuating the effect. The effect will be at first almost a function of voltage squared, thus agreeing with the measured results shown in Fig. 2. At the higher ranges of voltage, the maximum spread in a perfect vacuum would become less and less, as the voltage is raised. These two effects together explain why higher voltage beams reach their ultimate spreads more quickly as the gas pressure is decreased, but that the respective ultimate values of spread grow progressively less, as the voltage rises.

In carrying out experimental tests serving to substantiate the correctness of our theory and serving as a basis for the embodiment of our invention, apparatus arranged as shown in Fig. 1 was used. The upward kinks 19 and 21 of the axial potential curve were obtained by maintaining the drift tube at a potential negative with respect to both the second accelerating electrode and the collecting electrode, by an amount slightly greater than the voltage existing between the edge and the center of the beam when the latter consists only of unneutralized electrons. Due to the fact that the drift tube collects a current of stray electrons, merely placing a resistor in an external circuit between the drift tube and the aperture provides the necessary potential. Should stray electron current prove insufficient for this purpose, an auxiliary voltage supply could be used.

In a test made at 5×10^{-7} mm. of Hg vacuum pressure a 130 millampere beam spreading to twice its original diameter in 36 cm. at 7300 volts immediately stopped spreading when as little as

15 volts was applied between drift tube and adjacent electrodes in such direction as to reverse the gradients at these points. Since 15 volts variation from 7300 can have no appreciable electron lens or focusing effect per se, this result may be considered as successfully verifying the theory. Values of the spread variation with change of trapping voltage are given in Table I, below.

Table I.—Beam spread ion trap data

Pressure Mm. of Hg	V ₁	V ₂	Emission I	V _{final} - V drift	Spread R/R ₀
15	5×10 ⁻⁷	1,500	5,800	130	0
	5×10 ⁻⁷	1,500	5,800	130	7.5
	5×10 ⁻⁷	1,500	5,800	130	15.0
	5×10 ⁻⁷	1,500	5,800	130	30.0

As an auxiliary check, increasing the pressure to 5×10^{-6} also served to remove the spread, as illustrated in Table II, below.

Table II—Beam spread data

Pressure Mm. of Hg	V ₁	V ₂	Emission I	V _{final} - V drift	Spread R/R ₀
20	1.1×10 ⁻⁶	1,500	5,800	130	0
	3×10 ⁻⁶	1,500	5,800	130	0
	5×10 ⁻⁶	1,500	5,800	130	0

Of course, in actual use increasing the pressure is impractical since tubes are normally used as sealed off devices, so this latter Table II merely serves to demonstrate that the effect of extremely good vacuum in producing beam spreads could be removed by the use of an ion trap as suggested here.

It was noted in the test of ion trap voltage just described that for the particular beam used 15 volts removed practically all spreading and higher negative voltages produced very little increased effect, but no detrimental effects were observed when such higher negative voltages were used. It is to be remarked that this voltage is only slightly greater than the difference in voltage between the edge and the center of the beam when it consists of unneutralized electrons only. This voltage difference for any section on the beam would be

$$\frac{\rho}{6.94 \times 10^6}$$

where ρ is the number of unneutralized electrons per cm. length in the beam at that section. This is 10 volts for the particular beam chosen for the tests just described.

The reason for the comparable values is evident when it is considered that on the cathode side of the aperture the ions are always removed so fast that the electron beam is essentially unneutralized. Then the center of the beam is ten volts negative with respect to the edge and thus a negative gradient down which ions can flow will always be present until the drift space is lowered by this ten volts plus enough more to reverse the gradient produced by field penetration.

As shown by the above Table I, the voltage difference between the drift tube and its ends (back plate and aperture) to form an ion trap must be somewhat greater than 10 volts for a 50 millampere 6000 volt beam. The value necessary would increase directly as the current in the beam and vary inversely as the square root

of the voltage of the beam. Thus for a 3000 volt, 500 ma. beam it would be

$$10 \times 10 \times \sqrt{\frac{6000}{3000}} = 144 \text{ volts}$$

For a 5 ampere, 6000 volt beam it would be

$$10 \times \frac{5000}{50} = 1000 \text{ volts}$$

For beams of this magnitude the ratio of radii of the beam and surrounding drift tube also becomes of some importance.

The use of ion traps to keep beams from spreading at high vacuum greatly extends the limits of operation possible. In fact, arbitrarily dense beams will be maintained by ion cores at even extremely good vacuums (for example 10^{-9} mm./Hg) if sufficient volume be provided in the tube. Since an ion once in the unneutralized beam cannot leave it, and since virtually no recombination can take place, all molecules in a given tube at very high vacuum will soon be found as ions in the beam. The rest of the tube space will be practically empty. The volume necessary is given by the following relations for a 6000 volt beam:

Let the volume available = $N \text{ cm.}^3 = \text{S cm. A cm.}^2$

Let the length of the beam = $s \text{ cm.}$

Then

$$\frac{N}{s} = A = 3.75 \times 10^{-8} \text{ i amperes}$$

$P \text{ in mm./Hg}$

(Where the volume used has the same length as the beam, A gives the area necessary.)

Thus a 1 ampere beam at 10^{-8} mm./Hg needs only a volume the length of the beam with an area of 3.75 cm.^2 . For voltages other than 6000 volts this volume should be multiplied by

$$\sqrt{\frac{6000}{V}}$$

What we claim is:

1. An electron beam tube including means for generating electrons, means for producing a beam of said electrons, means for accelerating said beam, means for defining a substantially field-free space through which said beam passes, means for collecting said beam after passage through said field-free space, and means for maintaining said field-free space defining means at an electrostatic potential slightly negative with respect to said collecting means and with respect to the portion of said accelerating means adjacent said defining means.

2. The method of substantially preventing beam-spread of an electron stream within a field-free space which includes directing a beam of electrons within said space, establishing and maintaining a reverse potential gradient at least at one end of said field-free space, so as to trap positive ions therewithin.

3. A cathode ray tube system including means for generating and for collecting an electron stream in an atmosphere of not more than 10^{-5} mm./Hg, a field-free drift tube through which said stream passes, and means for maintaining the direct current potential of said drift tube slightly negative with respect to the potential existing adjacent the entrance thereof.

4. A beam tube including an electron source, an accelerating electrode held at a potential positive with respect to said source, a drift tube held at a fixed direct current potential slightly negative with respect to said accelerating electrode so as to prevent leakage of positive ions from said

drift tube, and means for collecting the electrons.

5. In the electron beam art, the method of projecting a beam over a distance without substantial spread thereof which includes the steps of establishing a substantially field-free space, passing through the space said beam, and establishing at each end said field-free space of a relatively slight potential gradient in the reverse direction to the normal potential gradient along the course of said beam, whereby positive gas ions are held within said field-free space so as substantially to neutralize the space-charge effects tending to cause spread of said beam.

15 6. A vacuum tube system including an accelerating electrode, a field-free drift tube insulated from other electrodes and means for keeping said drift tube slightly negative with respect to said accelerating electrode so as to prevent leakage of positive ions from said drift tube.

20 7. In electron optics, a system for reducing the spread of an electron stream due to space-charge effects, including a source of positive ions, a field-free chamber within which the ions are produced and through which said stream passes, and means for retaining said ions within said chamber, said last means comprising electrostatic means so connected as to establish at least at one end of said chamber a slight direct current potential gradient along said stream in a direction reverse to the gradient prevailing along said stream before the entrance thereof into said chamber.

25 8. The method of passing an electron beam through a field-free space without substantial beam-spread, which includes passing said beam through a slight reverse direct current potential gradient, immediately passing said beam through said field-free space and supplying gas molecules to said beam during its passage therethrough, whereby positive ions are formed, are substantially confined within said field-free space, and act substantially to neutralize the space-charge effect tending to cause spread of said beam.

30 9. A system for projecting a low impedance electron beam including conductive means defining a field-free chamber through which said beam is projected, gaseous means within said chamber producing positive ions under the impact of said beam, and electrostatic means maintaining at one end of said chamber a direct current potential gradient along said stream in a reverse direction to the potential gradient used in establishing said stream, whereby said ions are restrained within said chamber and act to neutralize the space-charge effect tending to spread said beam and increase the impedance thereof.

35 10. An electron beam tube for the production and projection of a beam of high density, including an electron source, an accelerating electrode establishing the beam, a drift tube through which said beam passes, means for keeping said drift tube at a slightly negative fixed direct current potential with respect to said accelerating electrode and means for collecting the electrons of said beam after passage thereof through said drift tube, whereby said negatively charged drift tube tends to retain therewithin positive ions formed from the residual gas within the beam tube.

40 11. A cathode ray tube system including means for generating an electron beam, means for accelerating said beam, means for projecting said beam through a tubular electrode and means for maintaining said tubular electrode at a direct current potential negative with respect to the potential of said accelerating means adjacent said tubular electrode by an amount which is less than one

half of one percent of the potential of said last-mentioned accelerating means so as to prevent leakage of positive ions from said tubular electrode.

12. A cathode ray tube system including means for generating an electron beam, means for accelerating said beam, means for projecting said beam through a tubular electrode, means for collecting electrons from said beam after its passage through said tubular electrode, and means for maintaining said tubular electrode at a direct current potential negative with respect to said collecting means by an amount which is less than one-half of one percent of the potential of said collecting means so as to prevent leakage of positive ions from said tubular electrode.

13. A cathode ray tube system including means for generating an electron beam, means for accelerating said beam, means for projecting said beam through a tubular electrode and means for maintaining said tubular electrode at a slightly negative direct current potential with respect to said accelerating means, the potential of said tubular electrode being sufficiently negative with respect to the potential to said accelerating means to prevent leakage of ions from within said tubular electrode but not sufficiently negative to substantially retard the speed of the electrons passing through said tubular electrode.

14. A cathode ray tube system according to claim 13 wherein the voltage difference between the voltage of the said tubular electrode and said accelerating means is

$$\frac{\rho}{6.94 \times 10^4}$$

where ρ is the number of unneutralized electrons per centimeter length in the beam at the section where it passes through the tubular electrode.
